UNITED STATES PATENT OFFICE

JAMES A. CARR, OF SAN FRANCISCO, CALIFORNIA, ASSIGNOR TO OWL DRUG COMPANY,
OF SAN FRANCISCO, CALIFORNIA, A CORPORATION OF NEVADA

DESIGN FOR A JAR OR SIMILAR CONTAINER

Application filed November 7, 1928. Serial No. 28,792. Term of patent 3½ years.

To all whom it may concern:

Be it known that I, JAMES A. CARR, a citizen of the United States, and a resident of the city and county of San Francisco, State of California, have invented a new, original, and ornamental Design for a Jar or Similar Container, of which the following is a specification, reference being had to the accompanying drawing, forming part thereof.

In the drawings:

Fig. 1, is a side view of the jar or similar container.

Fig. 2 is a plan view thereof.

I claim:

The ornamental design for a jar or similar container substantially as shown.

JAMES A. CARR.
